CLAIM

What is claimed is the ornamental design for a lamp, as shown and described.

DESCRIPTION

The instant application is a Continuation-in-Part of application Ser. No. 29/525,790, filed May 2, 2015; and application Ser. No. 29/526,069, filed May 6, 2015; both now pending.

FIG. 1 is a bottom perspective view of the lamp;

FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.

The wires suspending the lamp and the hinges interconnecting the segments are shown in broken lines and form no part of the claimed design. Furthermore, elements of the lamp have been broken away in some of the figures to indicate that no particular length is claimed. The portions of the lamp shown in broken lines form no part of the claimed design.
